CONTAINER STRUCTURE

Frank J. O'Brien, Pelham, N. Y., assignor to Continental Can Company, Inc., New York, N. Y., a corporation of New York

Application June 20, 1941, Serial No. 399,016

2 Claims. (Cl. 220—82)

The invention relates generally to container structures adapted to receive beverages or food products, and it primarily seeks to provide a novel container structure having a transparent end closure effective to prevent ingress of foreign matter while the containers are in transit or in storage prior to filling thereof and through which the interiors of the containers can be inspected with great facility prior to filling so as to insure against the filling of containers having bits of foreign matter therein.

In the packaging of beverages and foodstuffs in metallic receptacles it is essential that these beverages and foodstuffs be protected against direct contact with the metallic surfaces of the containers, and for this purpose it is customary to provide the containers with interior protective coatings of lacquer, enamel, or the like. These containers are shipped from the manufacturer to the user in partially completed state, that is with at least one end thereof open, and are filled with the beverage or food products by the user and then finally sealed for distribution and sale on the market. Obviously care must be exercised in avoiding the filling of containers which might have collected in the interiors thereof bits of foreign matter during the delivery of the containers to the user and storage by the user prior to the filling of the containers. The present invention is directed to the provision of a novel container structure which presents advantages in providing a protective surface interiorly of the container after it is filled, and also in providing a temporary transparent end closure which will permit inspection of the containers with great facility prior to filling thereof so as to assure against the filling of containers into which bits of foreign matter might have found their way during transit or storage.

An object of the invention is to provide a container structure having a transparent end closure through which the container can be interiorly inspected with great facility, said end closure being of a frangible nature, readily removable from the container if desired, or adapted to remain in the container after it is finally filled and closed to act as a protective medium preventing direct contact between the beverage or food product and the opposing end closure.

Another object of the invention is to provide a container structure including a transparent end closure of the nature stated and which is so applied to the container that the regular end closure intended to ultimately close the container after it has been filled can be temporarily and

removably assembled with the container while it is in transit or being stored before being filled.

With the above and other objects in view which will more fully appear, the nature of the invention will be more clearly understood by following the description, the appended claims, and the several views illustrated in the accompanying drawing.

In the drawing:

10 Figure 1 is a side elevation and part vertical cross sectional view of an inverted container embodying the invention, the regular end closure intended to ultimately seal the container being shown slightly separated from the end of the container.

15 Figure 2 is an enlarged fragmentary sectional view illustrating the end closure applied over the transparent end member, loosely and temporarily.

20 Figure 3 is a view similar to Figure 2 illustrating the end closure secured upon the container by the well known double roll seam.

25 Figure 4 is a view similar to Figure 2 illustrating a slightly modified attachment of the transparent end member.

30 Figure 5 is a fragmentary cross section illustrating a modified attachment of the transparent end member in which said end member is secured straight across the flanged bottom of the container.

35 Figure 6 is a view similar to Figure 2 illustrating an additionally modified attachment of the transparent end member.

40 In the drawing, the invention is shown applied to a large type of metallic receptacle or container, said container being of the type usually employed for packaging a gallon of syrup or beverage. The container includes a cylindrical body 5 terminating at its bottom in an outwardly directed flange 6 which is to be ultimately rolled into the bottom end closure securing seam. The container includes a cone top 7 terminating upwardly in a pouring throat 8 which is provided with an outwardly directed flange 9.

45 The open bottom of the container is closed by a transparent end member 10 which is in the nature of a frangible skin or film of "Cellophane" including a skirt portion 11 extending cup-like into the bottom of the container in the manner illustrated in Figure 1, and an edge portion 12 conforming to the shape of and adhesively attached to the outwardly turned bottom flange 6. The end closure cap 13 includes a centrally depressed portion which provides a heel or skirt 14 receivable in the end of the container within

the skirt portion 11 of the transparent end member, and an outwardly directed flange 15 which is rolled into the well known double roll seam during the ultimate closing of the container as illustrated at 16 in Figure 3. This cap or end closure is equipped with the usual sealing compound 17 which facilitates provision of a liquid tight seal.

When the containers thus formed are shipped from the manufacturer to the user at whose plant the filling and final closing of the containers take place, the pouring throat 8 may be temporarily closed against ingress of foreign matter by any suitable form of closure plug or dust cap, preferably a readily removable dust cap of the nature disclosed in detail in application for U. S. Letters Patent filed by John Haycock on April 8, 1939, Serial No. 266,804, which has matured into Patent No. 2,288,903. The bottom end closures 13 may be shipped separately from the containers or they may be temporarily inserted in the end thereof so that they can be readily removed prior to the filling of the containers. Thus protected at the top by the closure cap at the throat 8 and at the bottom by the end closure 10 and the end closure 13, or the transparent closure 10 alone, the container is protected against ingress of foreign matter in transit to the plant of the user or while stored at said plant.

When it is desired to fill the containers, this filling operation can be preceded by a careful inspection of the cans interiorly through the large area transparent end member 10 in order to assure against the filling of any containers which might have bits of foreign matter therein. The containers preferably are filled through the throat 8, but it will be obvious that the frangible transparent end member 10 can be removed, if desired, and filling of the containers effected through the large open bottoms thereof.

It is preferred, however, that the transparent end members be permitted to remain on the containers, and that the permanent end closures 13 be applied and secured in place thereover in the manner illustrated in Figure 3, for in this manner each end member 10 serves as a protective skin or film which is directly contacted by the beverage or food product in the container and prevents direct contact with the metal of the end closure 13. In containers thus formed and closed it is unnecessary to apply any lacquer or protective coating on the end closure 13.

In Figure 4 of the drawing there is illustrated a slight modification of the invention in which the transparent end member 10a is extended beyond and around the outwardly directed edge of the container bottom flange and adhered thereto as at 18.

In Figure 5 of the drawing an additional modi-

fication of the invention is illustrated in which the transparent end member is extended straight across the open bottom of the container, as at 10b, and is adhered to the outwardly turned flange thereof as at 19.

In Figure 6 of the drawing there is illustrated still another slight modification of the invention in which the transparent end member 10c is provided with only a relatively short skirt portion which extends only part way over the outwardly turned container body flange and is adhesively united thereto as at 20.

It is of course to be understood that the details of structure and arrangement of parts may be variously changed and modified without departing from the spirit and scope of my invention.

I claim:

1. A container having a large area open bottom end closed by a foreign matter excluding transparent end member adhered to said container and through which the interior of the container can be inspected with facility prior to filling, and a bottom end closure intended to ultimately seal the container and temporarily applied thereto over said transparent end member prior to filling of the container, said transparent end member being cupped a distance into the container bottom end, and said end closure including a depressed portion removably receivable in and contacting the cupped portion of the transparent end member in a manner for sustaining the cupped condition thereof.

2. A container having a filling opening at its top end and a large area opening at its other end, the latter opening being closed by a foreign matter excluding transparent end member adhered to said container and through which the interior of the container can be inspected with facility prior to filling, a single piece generally flat bottom end closure intended to ultimately seal the container and temporarily applied thereto over said transparent end member prior to filling of the container, said single piece end closure and the container end which it opposes having outwardly directed flanges adapted ultimately to be rolled together in a container sealing seam, and said transparent end member overlying the container end flange so as to be rolled into the seam between said flanges during the sealing of the container with the transparent end member forming a protective skin lying directly against said end closure throughout the whole of its area presented internally of the container thereby to separate food products or beverage in the container from direct contact with said end closure when the container has been filled and sealed.
